UNITED STATES PATENT OFFICE.

JAMES DOHERTY, OF CHICAGO, ILLINOIS.

BOILER CONSTRUCTION.

1,402,843.

Specification of Letters Patent. Patented Jan. 10, 1922.

Application filed September 20, 1917. Serial No. 192,371.

To all whom it may concern:

Be it known that I, JAMES DOHERTY, a citizen of the United States, residing at Chicago, in the county of Cook and State of Illinois, have invented certain new and useful Improvements in Boiler Constructions; and I do hereby declare the following to be a full, clear, and exact description of the invention, such as will enable others skilled in the art to which it appertains to make and use the same.

This invention relates to coal burning furnaces for steam or hot water heating, and like uses, and more particularly to that type of such furnace in which an overhead supply of supplemental combustion-supporting air is admitted to the fire-box for perfecting the combustion reaction, thereby rendering such furnaces capable of operation on bituminous coal without objectionable smoke and hence with corresponding thermal efficiency. The type of furnace referred to is well-known in this art and many different forms of it have been heretofore disclosed in patents but none of them, so far as I am aware, has resulted in a furnace equipment suited to the demands of the trade, or capable of the continued efficient service, as I have discovered is possible and practical by the organization of means hereinafter disclosed.

My invention consists in the manner of introducing and heating the supplemental air and in the structure of the air supply duct and its air distributing orifices and in the relation of such orifices to the fuel bed and the path of the fire gases, as well as in the organization of these features in the structure of sectional furnaces, all as hereinafter more fully described.

40 In the accompanying drawing, illustrating the preferred form of the invention, Figure 1 is a perspective of a sectional water-heating furnace with the side wall broken out and the interior parts shown in vertical and oblique sections.

Figure 2 is a partial face view of the water-curtain section.

Figure 3 is an enlarged cross-section of the water curtain, and

50 Figure 4 a detail showing a portion of the exposed or air-heating wall of the air duct.

The furnace illustrated comprises front and rear water-containing sections 1 and 3 and a series of intermediate water-containing sections 2, all having the same external contour and adapted to be clamped tightly

together, as usual in sectional furnaces, so that the water spaces in each section are put in communication, and the assembled sections form the walls of the fire box and the usual flue spaces by means of which the requisite surface is afforded for transfer of heat from the fire gases to the water. For this purpose, the sections constituting the front part of the furnace are provided with cross chambers 2' which are desirably T-shaped in cross-section, and form the roof or crown of the fire box. The furnace section next in rear of these crown sections, is provided with a water-containing cross member 60 or baffle D of considerable vertical dimension so that it depends well below the crown wall and forms a water curtain, marking the rear limit of the upper part of the fire box. The means for admitting the supplemental air is associated with the lower edge of this water curtain as presently explained. The cross chamber members 2^a of the furnace sections next in rear of the water curtain are spaced from each other forming flue spaces between them through which the fire gases rise to the upper horizontal side flues 4, above the fire box. In these side flues the gases flow forwardly over the crown wall 2^a, as indicated by the arrows and then turn and pass rearwardly through the horizontal center flue 8, to the take-off and chimney not shown. This flue arrangement is no different from furnaces long in common use and is the preferred, although not a necessary arrangement for the flues of the present invention. The bottom of the firebox is formed by a perforate updraft grate G which is parallel with the crown wall and substantially horizontal. The grate extends to the rear of the 80 water-curtain D and abuts against, or terminates adjacent to, an upright wall B which constitutes an ordinary bridge wall in the present case; its function is merely that of a retaining wall for the bed of fuel on the 85 grate. The upper front edge of this wall is shown in the drawing as bevelled and the level of a fuel bed of proper and normal depth is slightly below the lower edge of the bevel and about equal to the height of three 90 or four of the bricks of which the wall is made. The coal is supplied through the feed door 7 as usual and is generally deposited, initially, on the front part of the grate and worked to the rear as more coal is supplied. 95 Air is admitted to the fuel bed from the ash-pit entrance door and through the perforate 100

grate in the usual way and this constitutes the main supply of combustion-supporting air. The space in rear of the wall B, when that is a bridge wall as shown, serves merely 5 as part of the flue space or as a chamber for the collection of dust.

The lower edge of the water-curtain D extends transversely and horizontally over the rear part of the grate and fuel bed, occupying 10 a level which is somewhat nearer to the grate than to the crown wall 2', and in this position, it cooperates with the fuel bed directly below it, to form therewith a somewhat restricted passageway or throat 15 through which the fire-box opens into the flue space in rear. Practically all of the fire-gases developed in the furnace flow through this passage which extends across the furnace with practically uniform vertical dimension. The duct A for admitting 20 the supplemental air is coextensive with the water-curtain, being substantially coincident with its said lower edge and receives air from atmosphere, through appropriate, 25 damper controlled inlet openings 6 in the side legs of its furnace section as shown in Fig. 2 and discharges and distributes such air through a series of uniformly spaced and downwardly directed exit orifices opening 30 from the lower side of the duct and therefore toward the fuel bed. The air flow into and through the duct and its orifices is caused by the chimney suction which suffices to produce a vigorous discharge 35 through the row of orifices because the air path through the grate is more or less obstructed by the fuel and there is no other equivalent entrance for air to the interior of the furnace, besides which the location of 40 the duct is nearer to the chimney than other points in the fire-box. The single cross-duct supplies all the air that is needed for combustion which does not enter by way of the grate and supplies it at sufficient velocity 45 to cause it to penetrate the throat passage above mentioned and, seemingly to impinge against the subjacent bed of fuel creating an extraordinary mixing effect and turbulence in the fire gases at that point which is 50 manifested in practical operation by the development of a sheet of livid white flame extending directly from the water-curtain through the horizontal flues of the furnace. This effect is in part the result of the arrangement 55 of all the air duct orifices in a single transverse plane or zone over the rear part of the fuel bed and distinguishes my invention from that class of supplemental air furnaces in which the supplemental air is introduced through many separated orifices distributed over the whole area of the roof or sides of the firebox, as well as from other designs in which supplemental air is admitted without adequate velocity or 60 from orifices too remote from the fuel bed 65

to produce the necessary turbulence. Besides admitting the supplemental air in the proper relation and at the requisite velocity, it is found equally important that the air have an adequately high temperature before 70 it encounters the fire gases and I have ascertained that unless it exceeds a certain critical temperature, its effect on the efficiency of the combustion process will be found to be generally neutral or actually 75 negative. I have further ascertained that such critical temperature is not attained when the air duct is enclosed in water or water-jacketed; in such arrangements the air passing through the duct cannot exceed 80 the relatively low temperature of the water itself and that is much too low to produce the reaction referred to and cannot give the combustion efficiency which is the object of this invention. On the other hand, I have 85 also demonstrated, that any material increase of the air temperature above said critical point is not attended with any corresponding benefit to the reaction and is therefore not necessary, besides which the 90 use of such high temperatures involves serious difficulties on account of the rapid disintegration by the heat of the material of which the air duct is formed. The described location of the air duct, close over 95 the rear part of the fuel bed, is the hottest part of the furnace and so far as I am aware there is no refractory material, commercially available, that can permanently withstand such temperature. Previous efforts to construct air ducts in, or near this location, out 100 of various kinds of fire-brick have been unsuccessful on this account and the attempt to remedy the difficulty by admitting a larger volume of air through the duct, so 105 as to keep the temperature down, is not practicable, because any such air flow as would be effective for this purpose robs the fuel bed of its ash pit air supply and thereby impoverishes the primary combustion. 110

According to this invention a suitable temperature and a practical balance of conditions is obtained without encountering these difficulties. One of the walls, C of the air duct is arranged so as to be directly exposed for substantially the whole of its length to the radiant heat of the fuel bed, which, as stated, is very intense at this point, and said wall is thereby highly and also uniformly heated and transmits its heat to 115 the air flowing inside the duct. The other or opposite wall of the duct is shielded from the radiant heat and protected against acquiring so high a temperature by virtue of its proximity to the water in the curtain D, 120 the temperature of which is of course at all times relatively very low. This side of the duct is therefore kept relatively cool. The protection and cooling effect of the water, 125 supplemented by the cooling effect of the 130

incoming air, is found in practice to keep the exposed wall C at such temperature as to render it indefinitely immune from thermal deterioration, while the air flowing behind it acquires a temperature high enough to adapt it for immediate chemical combination with the fire gasses in ordinary operation, and to produce the characteristic and efficient flame effect above referred to. By such organization and partial protection and cooling of a duct otherwise highly heated for its full length, its combustion-perfecting function is made available in the fullest degree.

The preferred air duct passage as shown in the drawing is formed in part by the metal wall of the water-curtain itself, which is provided along its lower edge with a series of forwardly projecting teeth F, all of substantially equal size and containing water, and in part by the separately made wall member C above referred to, which is of angle-bar cross section and seated upon the tips of the teeth, as indicated in Figure 3, thus forming the duct passage A with the spaces between the teeth forming the downwardly directed air orifices. The said spaces are about the same width as the teeth so that the air is delivered as closely adjacent and also uniformly spaced, jets or blasts, approximating the form of a continuous sheet of air. The wall C, being structurally separate from the water-curtain wall and longitudinally coextensive with it and also being supported intermediate of the ends of the duct upon the water curtain, besides having a simple cross-section, is entirely free to expand and contract under thermal change without injury to itself and without imparting strain to the metal of the water-curtain proper, while nevertheless sufficing as stated to establish the requisite temperature in the supplemental air. While I am not able to give the exact value of the critical air temperature which I mentioned above, because of the difficulty of measuring it, it will be sufficient to those skilled in this art to say that it is attained by substantially the extent of wall exposure to the radiant heat as is shown in the drawing. It is to be further noted that in the drawing the air jets are directed downwardly and also slightly forwardly but it is by reason of the downward direction and the velocity that the turbulent effect is attained; if otherwise, the air will merely lick around the lower edge of the duct or water-curtain and pass off with the flue gases without mixing or sufficiently combining therewith.

In connection with the statement above made that the air duct provides for the introduction of all the combustion supporting air except that which enters through the grate, it will of course be understood that in every furnace there is inevitably

more or less air leakage especially at the feed door, and that the feed door may be provided, as in the present case, with an air damper for controlling the entrance of outside air above the fuel. Ordinarily, the effect of air admission through such damper is to chill or suppress the combustion rather than otherwise, such dampers being principally useful when the fire is banked. Under certain conditions and with certain kinds of coal a limited admission of air at the feed door may serve to support combustion, but in any event the amount of air leakage, if any, and the amount admitted through the feed door damper, is relatively negligible as respects its effect on the flow through the cross duct, so that it does not destroy the entering velocity of the latter and the mixing effect which is dependent thereon, and it is therefore true that the said duct and the ash pit together admit substantially the whole supply of the combustion supporting air.

The firebox side of the water-curtain above the air duct is faced with a refractory material represented in the present case by tiling 5; this refractory surface becoming highly heated is found to lend assistance to the combustion in the fire-box—possibly by the so-called regenerative effect. The water-curtain is also formed with one or more small apertures E in its upper part adapted to cause a slow withdrawal of gases from beneath the crown wall and for the purpose of insuring the continuous presence of very hot gases contiguous to said wall so as to utilize their heating effect in the crown wall water.

Claims:

1. In a furnace of the type described, the combination with a fire-box having a horizontal, perforate updraft grate and a main air supply through the grate, of a transverse baffle wall containing water and coacting with the rear part of the fuel bed on said grate to form therewith a throat passage, means for admitting supplemental heated air to the fire-gas flow in said passage comprising an air duct associated in parallel relation with the lower edge of said wall, one side of said duct being exposed to the radiant heat whereby it heats said supplemental air, and the other side being shielded therefrom and subject to the cooling effect of the water in said wall, and means constituting the exit from said duct adapted to direct said heated air crosswise of the gas flow through said passage, said air duct exit and main air entrance being correlated to produce a velocity of said heated air flow adapting it to mix with said fire-gas flow.

2. In a furnace of the type described, the combination with a fire-box having a horizontal, perforate updraft grate constituting an entrance for some of the combustion sup-

- porting air, of an entrance for substantially all the balance of the combustion supporting air consisting of a transverse air duct extending directly over and spaced above the 5 burning fuel bed at the rear part of said grate and forming with said bed the principal fire-gas flow passage from the fire-box, said duct being associated with means whereby it is protected by water on one side and subject to 10 the radiant heat of the combustion on another side, whereby the air flow therein is heated, and provided with downwardly directed exit means adapted to cause mixture of said heated air with the gas flowing 15 through said passage.
3. In a furnace of the type described, the combination of a fire-box having a horizontal, perforate up-draft grate constituting an entrance for some of the combustion sup- 20 porting air and an entrance for substantially all the remainder of the supply of combustion-supporting air comprising a row of air orifices extending transversely over and at a uniform distance above the whole fuel bed at 25 the rear part of said grate and an air duct for conducting the air to said orifices comprising a wall having means spaced above the fuel bed for protecting it by water, and another wall uniformly subjected to the radi- 30 ant heat of the combustion and serving to heat the air issuing from said orifices.
4. In a furnace of the type described, the combination with a fire-box having a perforate updraft grate constituting an entrance 35 for combustion-supporting air, of a transverse fire-box wall containing water disposed over the rear part of the fuel bed on said grate, means for admitting substantially all the rest of the combustion-supporting air to 40 the fire gas flowing between said wall and fuel bed, comprising a transverse air duct situated directly in front of the lower water-containing edge of said wall, one side of said air admitting means being exposed to the 45 radiant heat of the combustion and the rear side thereof being shielded therefrom and subjected to the cooling effect of the water in said wall, and means for directing the heated supplemental air toward the fuel bed 50 and adapted to cause the same to mix with the fire gas flow beneath said wall.
5. In a furnace of the type described, the combination with a fire-box having a perforate updraft grate constituting the main 55 air supply, of a transverse fire-box wall containing water and having its lower edge disposed directly over the rear part of the fuel bed on said grate and nearer to the grate than to the fire-box roof, means for admitting supplemental air to the fire gas flow beneath said wall comprising a transverse air duct associated in parallel relation with said lower edge, one of the walls of said duct being exposed to the radiant heat of the com- 60 bustion and another being shielded there- 65 from and subjected to the cooling effect of the water in said wall, and a row of air exit orifices in said duct arranged to direct heated air jets toward the fuel bed, said main and supplemental air entrances constituting substantially the whole supply of combustion supporting air to the fire-box.
6. In a furnace of the type described, the combination with a fire-box having a horizontal perforate up-draft grate and a main 70 air supply through the grate, of a transverse water-curtain forming the rear boundary wall of the fire-box, means for admitting heated supplemental air to the passage beneath said water curtain comprising an air 75 duct associated with the lower edge of said curtain and partly protected thereby against the radiant heat and having an air-heating wall directly exposed to the radiant heat and an exit adapted for directing the heated air 80 from said duct toward the grate.
7. In a furnace of the type described, the combination with a fire-box having a horizontal, perforate up-draft grate and a main air supply through the grate, of a supple- 85 mental air admission duct disposed substantially horizontally and transversely over and out of contact with the rear part of the burning fuel bed on said grate and providing a fire-gas passage between the same and 90 said bed, said duct being formed by transverse wall members, one of which is water-protected and one of which is subject to the radiant heat of the combustion and having downwardly directed exit means adapted to 95 discharge highly heated air crosswise into the fire-gas flow through said passage.
8. In a furnace having a horizontal, perforate up-draft grate constituting a main 100 air supply, a supplemental air-supply comprising a transverse air-distributing passage disposed over the rear part of the fuel bed on said grate and open to atmosphere at the side of the furnace and constituted of separate passage-forming wall members, means 105 for keeping water in contact with one of said passage forming wall members, the other member being directly exposed to the radiant heat of the combustion whereby it transmits heat to said supplemental air, said 110 passage having air exit means directed toward the fuel bed.
9. In a furnace having a horizontal up-draft perforate grate constituting an entrance for part of the combustion-supporting air supply, an entrance for substantially all the rest of said air supply comprising a transverse, substantially straight, air-distributing passage composed of separate 115 passage-forming members, means for keeping water in contact with one of said passage forming wall members, the other member being exposed to the radiant heat, and both of them being disposed directly over the fuel bed, and the passage formed thereby having 120
- 125
- 130

inlets from atmosphere through the sides of the furnace, in alignment with said passage, and having downwardly directed air-exit means.

- 5 10. A furnace of the type described comprising the combination of a grate, a water-curtain located above the fuel bed on said grate and provided with projecting teeth, and a separate member co-acting with said water-curtain to form an air passage, said passage having entrance means for air and the spaces between said teeth serving as air-distributing outlets from said passage.

11. In a furnace of the type described, the combination with a grate, of a transverse, water-containing baffle wall located above the fuel bed thereon and forming the rear of the fire-box space, and a separate member mounted on said wall and forming there-20 with a supplemental air admission duct hav- air air exit means.

12. In a furnace of the type described, the combination with a grate, of a water-containing member provided with toothlike 25 projections and a member of angled cross-section supported by said projections and forming an air-admitting and air-distrib- 90 uthing passage.

13. In a furnace of the type described, the combination with a grate and a transverse water-curtain forming the rear wall of the fire-box space and a separately formed member supported intermediate of its ends on said water-curtain and associated therewith 35 to form an air-admitting and air-distrib- 95 uthing cross duct exposed to the radiant heat on one side and protected by the water in said curtain on another side.

14. In a sectional furnace, the combination with front, rear and intermediate water-containing sections all made of similar external contour and assembled to form the furnace body with internal chambers constituting flue and fire-box spaces, of 45 means carried by one of said intermediate water-containing sections constituting a depending water-containing fire-box wall and also constituting an air-conducting and distributing passage, said passage extending 50 crosswise of the furnace above the fuel bed and having an opening to atmosphere at its end intersecting the side of said intermediate water-containing section.

15. In a sectional furnace of the type de-55 scribed, the combination with a series of front water-containing sections all of similar external contour assembled to form the front part of the furnace containing a fire-box space and having an up-draft grate, of a 60 water-containing section of similar external contour assembled in rear of said front fire- 115 box sections and carrying a depending trans- 65 verse water-containing wall situated over the rear part of said grate and a transverse air-distributing passage located above said

grate and directly in front of the lower portion of said water-containing wall whereby the water in said wall lies horizontally in rear of said air passage, and another water-containing furnace section or sections 70 of similar external contour assembled in rear of said wall-carrying section to form the rear part of the furnace.

16. In a sectional furnace of the type de-75 scribed, the combination with a series of water-containing sections all of similar external contour assembled to form the front part of the furnace and containing and forming a crown wall with horizontal flue spaces above it and a fire-box space beneath 80 it, and a grate for said space, of an intermediate water-containing and flue-forming section of similar external contour assembled in rear of said series and having its water space extended downwardly to form a water 85 curtain depending below said crown wall and over the grate, an air-admitting and air-distributing cross duct having downwardly directed air exit means, the walls of said duct being supported intermediate of 90 their ends on said intermediate or water curtain section and another water-containing section or sections also having a similar external contour assembled in rear of said water-curtain section to form the rear part 95 of the furnace.

17. In a sectional furnace of the type de-100 scribed, the combination with a series of front water-containing sections, all of similar external contour, assembled to form the front part of the furnace and containing a crown wall with flue spaces above it and a fire-box space beneath it, of a water-containing and flue-forming section in rear of said series, means wholly carried by said 105 last named section constituting a transverse water-curtain depending below said crown wall and also constituting an air-admitting and air-distributing cross duct adjacent the lower edge of said water curtain. 110

18. In a furnace of the type described, the combination of a fire-box, an updraft grate, constituting the main supply of combustion-supporting air, a transverse water-containing baffle forming the rear wall of 115 said fire-box having an air duct associated with its lower edge adapted to deliver substantially all of the balance of the air required for combustion into mixing relation with the fire gases passing beneath said 120 baffle and also having a facing of refractory material on its front surface.

19. A sectional furnace of the type de-125 scribed composed of a front, a rear and several intermediate water-containing sections, all of similar external contour and all assembled together to form the furnace with internal parts constituting flue spaces and a fire box, and an updraft grate constituting the main air supply to the fire box, in com- 130

bination with a supplemental air admission duct adapted to introduce substantially all the balance of the air required for combustion and disposed substantially horizontally 5 and transversely over and out of contact with the rear part of the burning fuel bed on said grate, and providing an open fire-gas passage between itself and said fuel bed, said duct being formed by transversely extending wall members, one of which is constituted by a water-containing part of one

of said intermediate furnace-sections and one of which is constituted by a horizontally extending member associated with said intermediate section and subject to the radiant 15 heat of the combustion, said duct having downwardly-directed air exit means adapted to discharge the highly heated supplemental air crosswise of, and into mixing relation with, the fire-gas flow through said passage. 20

In testimony whereof I affix my signature.
JAMES DOHERTY.
